ATTORNEY

UNITED STATES PATENT OFFICE.

ALFRED HERSCHEL, OF NEW YORK, N. Y.

SOUND-PRODUCING INSTRUMENT

Application filed September 25, 1925. Serial No. 58,627.

This invention relates to improvements in sound producing instruments and has particularly reference to a loud speaker for use in connection with radio receiving apparatus.

- 5 The principal object of the invention resides in a loud speaker of the cone type in which the sound is produced with greater clarity and strength than those heretofore constructed as the concave surface of the 10 playing cone is exposed directly to the atmosphere, while any vibrations which may penetrate the convexed side of the cone are trapped and directed forwardly with the vibrations of the playing cone.
- 15 Another object of the invention is the provision of a loud speaker in which the amplifying cone is flexibly supported at its outer periphery within a second cone or casing so that the full qualities of the amplifying 20 cone are utilized.

A further object of the invention is to provide a loud speaker which is simple in construction, inexpensive of manufacture and highly efficient for the purpose intended.

- 25 With these and other objects in view, the invention resides in certain novel construction and combination and arrangement of parts, the essential features of which are hereinafter fully described, are particularly 30 pointed out in the appended claims, and are illustrated in the accompanying drawing, in which:—

Figure 1 is a side elevation of my improved loud speaker.

- 35 Figure 2 is a vertical longitudinal sectional view therethrough.

Figure 3 is a sectional view showing a slight modified form.

- Referring more particularly to the drawing, the reference numeral 10 designates my 40 improved loud speaker in its entirety and which includes a base 11 to which one end of a vertically extending post or standard 12 is threadedly connected. The post is hol- 45 low or tubular for the passage of wires to be presently described. The other end of the post or standard is threadedly connected to a hollow globular shaped head 13, which supports a conical shaped casing 14. The 50 casing 14 may be constructed of any suitable material such as metal, fiber board or parchment, and the narrow or pointed end of the casing extends through an opening 15 in the head and is secured therein in any suitable 55 manner. A wall 16 is mounted in the re-

60 electric sound producing unit 17. A shaft 18 extends from the unit through the head to the exterior of the same, so that the armature in the unit may be adjusted to prevent the locking of the same to overcome any possibility of distortion in the instrument.

65 Supported within the casing 14 is a cone shaped diaphragm or amplifying cone 19, the apex of which is provided with an aperture 20 through which the vibrating pin 21 of the unit 17 extends. A pair of disks 22 are mounted on the pin and engage opposite sides of the cone, while a nut or other retaining member 23 is threaded to the free 70 end of the pin.

75 The amplifying cone 19 is spaced from the walls of the casing to provide a chamber 25 and the said cone is constructed of parchment and has its outer peripheral edges loosely engaging the inner walls of the casing, so that the cone 19 is free to vibrate. If desired, the edges of the casing and cone may be bound with a braid for imparting a finished appearance to the device but the 80 braid must have yielding qualities to allow the cone to vibrate. Wires 24 connect the device with the radio receiving set and extend through the base 11, post 12, and head 13 to the binding posts on the unit 17.

85 In practice, we shall presume that the device is connected with a radio receiving outfit and at which time the electrical impulses will be transferred into sound impulses through the unit 17. As the pin 21 vibrates, the impulses are transferred to the cone 19 from where they are amplified and emitted outwardly to the atmosphere from the concave side thereof. It is, of course, understood that sound emitted from 90 a concave surface is greater than from a convexed surface but it is possible that a certain amount of sound waves may penetrate the parchment to the concave side of the cone. These waves are stopped or 95 trapped within the chamber 25 and strike against the concave side of the casing from where they are projected forward in the same direction as those from the concave side of the cone 19. It will therefore be 100 seen that the sound produced by the device is concentrated and thrown in one direction, so that a clear and better tone is produced.

105 In Figure 3 of the drawing, I have shown a slightly modified form of casing 14' which is of a different shape than the casing 14 shown in the preferred form. The re-

mainder of the parts are identical with those shown in the preferred form and it will be appreciated that the casing if desired may be of various other shapes without in any 5 way departing from the spirit of my invention.

What is claimed as new is:—

1. A loud speaker comprising a base member, a hollow head supported above said 10 base, a conical shaped casing having its apex extending into said hollow head and supported thereby, said casing adapted to contain an electrical sound producing instrument, and a cone shaped diaphragm sup-

ported by said sound producing instrument 15 and disposed within said casing with its free edge loosely disposed therein.

2. A loud speaker comprising a base member, a casing supported by said base member and adapted to contain an electrical sound 20 producing instrument, and a cone shaped diaphragm supported by said sound producing instrument and disposed within said casing with its free edge loosely disposed therein. 25

In testimony whereof I have affixed my signature.

ALFRED HERSCHEL.
